[57] CLAIM

The ornamental design for an hydraulic oil tank for use
in cement trucks, as shown and described.

DESCRIPTION

FIG. 1 is a top right perspective view of a hydraulic oil
tank for use in cement trucks showing our new design;
FIG. 2 is a side elevational view thereof;
FIG. 3 is an opposite side elevational view thereof;
FIG. 4 is a front elevational view thereof;
FIG. 5 is a rear elevational view thereof;
FIG. 6 is a top plan view thereof;
FIG. 7 is a bottom plan view thereof.

FIG. 1

FIG. 2

FIG. 3

FIG. 4

FIG. 5

FIG. 6

FIG. 7
